FRAME FOR A COMBINATION RUBBER AND PLASTIC MILL

Luther K. Bates, Trenton, N. J., assignor to William R. Thropp & Sons Corp., Trenton, N. J.

Application November 24, 1952, Serial No. 22,426

Term of patent 14 years

(Cl. D55—1)

To all whom it may concern:

Be it known that I, Luther K. Bates, a citizen of the United States, residing at Trenton, in the county of Mercer and State of New Jersey, have invented a new, original, and ornamental Design for a Frame for a Combination Rubber and Plastic Mill, of which the following is a specification, reference being had to the accompanying drawing, forming a part hereof.

Fig. 1 is a plan view of a frame for a combination rubber and plastic mill, showing my new design.

Fig. 2 is a side elevation of the frame shown in Fig. 1.

Fig. 3 is an end elevation, as viewed from the left of Figs. 1 and 2.

Fig. 4 is an end elevation as viewed from the right of Figs. 1 and 2.

The side opposite that in Fig. 2 is substantially plain.

I claim:

The ornamental design for a frame for a combination rubber and plastic mill, substantially as shown and described.

LUTHER K. BATES.
